PATIO COVER

Joseph Schlager, 9051 Hickory Place, Thornton, Colo.

Filed Mar. 31, 1960, Ser. No. 59,974

Term of patent 14 years

(Cl. D13—1)

The roof of the patio cover is plain and unadorned.

1 claim:

The ornamental design for a patio cover, as shown and described.
